UNITED STATES PATENT OFFICE.

CHRISTOPHER R. ABBOTT, OF ANDERSON, INDIANA.

FURNACE CONTROL MECHANISM.

Application filed August 1, 1921. Serial No. 488,907.

To all whom it may concern:

Be it known that I, CHRISTOPHER R. ABBOTT, a citizen of the United States, and a resident of Anderson, county of Madison, 5 and State of Indiana, have invented a certain new and useful Furnace Control Mechanism; and I do hereby declare that the following is a full, clear, and exact description thereof, reference being had to the accompanying drawings, in which like numerals refer to like parts.

This invention relates to furnace control mechanism and the chief object thereof is to provide simple and positive means for controlling the check and draft controls of a furnace.

The features of the invention are such as will accomplish all of the foregoing objects.

The full nature of the invention will be understood from the accompanying drawings and the following description and claims.

In the drawings, Fig. 1 is an elevational view of a furnace with the invention associated therewith. Fig. 2 is a top plan view of the invention. Fig. 3 is a side elevational view of the invention. Fig. 4 is a sectional view taken on line 4—4 of Fig. 2.

In the drawings 10 indicates a heating device or furnace, that herein illustrated being of the hot water type, and said furnace or heating device is provided with the usual draft 11, closed by a hinged plate 12 and a smoke pipe 13 controlled by a check valve 14. Herein the particular type of mechanism associated with the draft and check means or controls, is a rock shaft 15 movable by a counterweighted lever 16 associated with which is the counterweight 17. The lever is also associated through the rod or cable 17 with the draft valve or plate 12. This control mechanism is old in the art and forms no part of the invention, and the particular type herein illustrated is such that 45 the control is automatic, that is, that the furnace is provided with means such that as the steam pressure increases beyond a pre-determined pressure, the counterweighted lever closes the draft and opens the check, 50 and when the pressure of the steam heating system decreases, the same mechanism is adapted to open the draft and close the

check, thereby maintaining a uniform condition. This feature is temperature operable, as well as pressure operable, and in the latter instance would be thermostatically controlled.

Heretofore it has been the custom when the automatic control is to be rendered inoperative, such as during the night when the fire is to be checked, suitable means has been provided for locking the lever 16 so that the same will not be movable by the counterweight 17 and the controlling means heretofore described. Also it has been the custom to disconnect the cable means 17 from said lever, thereby insuring that the draft will not be opened. In the present invention one end of the lever 16 is connected to a cable or chain 20 which is associated with suitable pulley means 21 and terminates in a ring 22. The full and dotted line positions in Fig. 1 illustrate the respective positions of the check and draft valves and the main controlling lever 16. Thus, when the parts are 75 in the full line position as shown, the check is open and the draft is closed; while in the dotted line position, the check is closed and the draft is open. It will be apparent that if suitable means is provided to hold the chain or cable 20 in its full line position, the fire in the furnace will be checked, and that when the cable means 20 is released, the draft will be opened. Means is provided for maintaining the cable 20 in its latched position 80 and releasing the same at the desired time, and is illustrated in detail in Figs. 2, 3 and 4.

In said figures, 25 indicates a base member which carries at one end a bracket 26 which is slotted as at 27, and extending 90 through said bracket and transversely of the slot 27 are the aligned openings 28. The slot 27, as shown clearly in Figs. 1 and 3, is adapted to receive the ring 22. A suitable bolt member 29 slidably supported in the 95 aligned openings 28 is adapted to maintain upon or lock the ring to the bracket. The opposite end of the bolt 29 is likewise slidably supported in a bracket 30 secured to the base plate 25. The bracket 30 has an opening 31 in alignment with the aligned openings 28. Concentric with the bolt 29 is a coiled spring 32 which bears at one end 100 against the bracket 26 and at the other end

- bears against a collar 33 which is herein shown formed integral with the bolt member 29. Thus when suitable latching means associated with the bolt member is released, 5 the spring 32 slides said bolt in the aligned openings and permits the ring 22 to escape therefrom. The means for compressing the spring 32 and moving the bolt simultaneously therewith into the locking position, 10 comprises a lever 34 which is hingedly supported at 35 upon the base plate 25, and said lever, as shown clearly in Figs. 2 and 4, straddles the bolt 29 and bears against the collar 33.
- 15 The means for latching the bolt 29 comprises a catch member 36 which is pivotally supported at 37. One end of said catch member, which is essentially a lever, is provided with a counterweight 38 for maintaining said lever in the position shown in Fig. 4, whereby the bolt 29 is secured in the position shown in Figs. 2 and 3. A suitable extension 39 of the bracket 30 carries a guide member 40 which limits the transverse movement of the lever 36, but permits its rocking movement on the pivot 37 in a plane perpendicular to the movement of the bolt 29. The other end of the lever 36 or latching member is provided with a tripping portion 41 herein shown in the form of a padded plate 41. Suitably supported on the extension 42, which provides a pivotal support for the lever 36, is an overhanging portion 43 which carries an adjusting member 44 which may 30 be locked in adjusted position by a lock nut 45. The adjusting member 44 is herein shown in the form of a bolt which engages a transversely extending portion 46 on the lever 36, and it is by the aforesaid means 35 that the normal position of the lever 36 is adjusted. Also positioned upon the base member 25 is a supporting plate 50 which terminates in an extension 51 substantially parallel to the lever 36. The extension 51 comprises a circular portion 52 and a wing portion 53. A suitable clock 54 is provided with a dial 55, the usual alarm dial 56 with the several hands 57, the winding devices 58 and the setting devices 59. Said clock carries 40 a complementarily formed socket member 60, and said member is key-hole shaped to receive the circular and wing portion of the supporting bracket 50. The base member 25 is herein shown provided with a slot 61 so that the extension 51 does not project 45 very far beyond the base 25. The clock 54 is provided with the usual alarm hammer 62 which usually is adapted to strike the alarm bell, but in the present instance is 50 positioned adjacent to the plate 41 and is adapted to strike the same, thereby tripping the lever 36 on its pivot 37 in opposition to the weight 38 to permit the bolt 29 to be projected by means of the spring 28 into 55 such position that the ring 22 will be released from the bracket 26, thus permitting the weight 17, see Fig. 1, to become operative to actuate the lever and thereby open the draft 12 and close the check 14.
- The invention claimed is:
1. In a clock controlled device, the combination of a clock, yieldingly mounted releasable means, latching mechanism therefor and releasable by said clock, a weight for maintaining said latching mechanism in the latching position, and means for adjusting the latching position of said latching mechanism. 70
2. A releasing mechanism in combination with a cable normally under tension and a retaining member therefor, including a bearing bracket having a slot therein communicating with and extending transversely of said bearing, for receiving said retaining member, a bolt slidably supported in said bearing bracket and having an end adapted to bridge said slot for retaining said retaining member and said cable and means for sliding said bolt to remove the same from the slot and releasing said member and said cable from the tension. 80
3. A releasing mechanism including a plurality of bearing brackets, one end bracket having a slot therein communicating with and extending transversely of the bearing, a bolt slidably supported in said bearing brackets and having an end adapted to bridge said slot for retaining purposes, retaining means adjacent the other end bracket for retaining the bolt in the bridging position, and yielding means for sliding the bolt from the bridging position when the retaining means is actuated. 90
4. A releasing mechanism including a plurality of bearing brackets, one end bracket having a slot therein communicating with and extending transversely of the bearing, a bolt slidably supported in said bearing brackets and having an end adapted to bridge said slot for retaining purposes, retaining means adjacent the other end bracket for retaining the bolt in the bridging position, an abutment rigid with said bolt, a coiled spring having one end bearing on said abutment and the other end stationarily secured, and a movably mounted resetting member for engaging the opposite side of the abutment for returning said bolt to the bridging position in opposition to said spring. 100
5. A releasing mechanism including a plurality of bearing brackets, one end bracket having a slot therein communicating with and extending transversely of the bearing, a bolt slidably supported in said bearing brackets and having an end adapted to bridge said slot for retaining purposes, retaining means adjacent the other end bracket for retaining the bolt in the bridging position, an abutment rigid with said bolt, a 110

- 130

coiled spring having one end bearing on said abutment and the other end stationarily secured, a movably mounted resetting member for engaging the opposite side of the abutment for returning said bolt to the bridging position in opposition to said spring, and means associated with the retaining means for automatically returning said retaining means to the retaining position simultaneously with the return of the bolt to the bridging position. 10

In witness whereof, I have hereunto affixed my signature.

CHRISTOPHER R. ABBOTT.
